CLAIM

The ornamental design for a luminaire, as shown and described.

DESCRIPTION

FIG. 1 is a top isometric view of a luminaire showing my new design;

FIG. 2 is a bottom isometric view of the luminaire shown in FIG. 1;

FIG. 3 is a front elevational view of the luminaire shown in FIG. 1;

FIG. 4 is a right side elevational view of the luminaire shown in FIG. 1;

FIG. 5 is a rear elevational view of the luminaire shown in FIG. 1;

FIG. 6 is a left side elevational view of the luminaire shown in FIG. 1;

FIG. 7 is a top plan view of the luminaire shown in FIG. 1; and,

FIG. 8 is a bottom plan view of the luminaire shown in FIG. 1.

The broken lines represent portions of the luminaire that form no part of the claimed design.

1 Claim, 7 Drawing Sheets
